HOMER H. HOLCOMBE, OF BIRMINGHAM, ALABAMA, ASSIGNOR, BY MESNE ASSIGNMENTS, TO HOLCOMBE TEXTILE EQUIPMENT CO., INC., OF BIRMINGHAM, ALABAMA, A CORPORATION OF ALABAMA

BUNCH-BUILDER ATTACHMENT

Application filed May 3, 1924. Serial No. 710,778.

This invention relates to spinning frames, and more particularly to the builder motion thereof which controls the laying on or winding of the yarn or thread upon the yarn receivers or bobbins that are mounted upon rotating spindles. The bobbins, as now generally used in the shuttles of automatic filling replenishing "feeler looms", are wound with a preliminary winding or bunch of yarn laid at the base of the feeler wood before the main or service winding is laid. When the yarn has been substantially woven off in the loom sufficiently to effect a change of filling it is contemplated that this preliminary winding or bunch will be left on the bobbin and will comprise sufficient yarn to enable the shuttle to be passed one or more times across the loom without causing a mispick or thin place in the cloth.

In my pending application, Serial No. 603,437, I have shown and claimed generically an automatic bunch builder attachment comprising a driving gear deriving motion from the builder cam shaft and a segmental driven gear movable with the builder rack and adapted to be brought automatically into mesh with the driving gear when the frame is doffed so that when the frame is started up the engagement of the two gears will act to hold the builder rack in position to lay the bunch winding with the proper traverse at the base of the feeler wood before the rack is released to the control of the main builder cam.

One object of my present invention is to simplify and perfect the automatic means for bringing the segmental driven gear into mesh with its driving gear and to this end I contemplate using a latch which is movable responsive to the winding up of the traverse chain on the drum after the lowering of the ring rail and which, as thus moved, will cause the driven gear to mesh with the driving gear.

My invention also contemplates novel means for automatically disengaging the latch from the driven gear as it is rotated, the driven gear being adapted automatically to assume idle position after moving out of mesh with its driving gear and until again engaged and moved into mesh by the latch.

My invention also contemplates improvements in the design of the segmental driven gear and in the means for adjusting the effective arc subtended by it thereby to control the length of the thread or yarn that will be wound in the bunch. 55

My invention also comprises the novel details of construction and arrangement of parts, which in their preferred embodiment only are illustrated in the accompanying drawings which form a part of this specification, and in which:— 60

Fig. 1 is a side elevation showing conventionally a builder rack equipped with my bunch building mechanism shown in idle position. 65

Fig. 2 is a plan view of Fig. 1.

Fig. 3 is an enlarged detail view of the segmental gear with its controlling latch shown about to move the gear into operating position. 70

Figs. 4 and 5 are similar views of the builder mechanism, Fig. 4 showing the latch about to be disengaged after the gears are in mesh, and Fig. 5 showing a position assumed by the latch during the building of the bunch. 75

Fig. 6 is a detail view of a bobbin with the bunch windings in full lines and the main windings dotted.

Similar reference numerals refer to similar parts throughout the drawings. 80

I have illustrated my invention in connection with a typical builder rack 1, and since its use involves no change in the other standard parts of a spinning frame, I will omit any illustration or description of the latter as such would encumber the specification and drawing with needless details. 85

The conventional builder rack shown carries the usual drum 2 upon which is wound a chain 3 that is hooked to the main traverse chain 4. This chain 4, in the manner well understood in the art, controls the position of the ring rail and the winding of the yarn on the bobbins 30. On the outer end of the builder rack is a pick wheel 5, the rotation of which, automatically responsive to movements of the rocker bar, will through a worm 6 unwind the drum 2. The builder rack is provided on one side with a pitman stand 90

7 of any usual design on which is mounted a pitman roller 8 that is adapted to be engaged by the main builder cam 9. This cam 9 is mounted on a shaft 10 driven in any 5 suitable manner from the main drive of the spinning frame, and its engagement with the pitman roller will give the builder rack 1 the rise and fall which is transmitted to the traverse chain 4 to give the requisite traverse 10 for applying the main windings 31 to the bobbins. All of the parts as thus far described are of standard construction and may 15 obviously be varied according to the type of spinning frame to which my invention is to be applied.

My improved bunch building mechanism for automatically building the preliminary winding or bunch of yarn 32 at the base of the feeler wood 33 of bobbins 30, comprises 20 a driving element preferably a gear 11 fast on the shaft 10, though it may be driven in any suitable way so long as its drive is co-ordinated with the drive of the main builder cam 9. A slotted bracket 12 is attached to 25 the builder rack 1 in any suitable manner, preferably by the use of one of the standard bolts 13 in the rack, the slot being provided in the bracket to enable it to be adjusted to suit different types of racks. I mount a 30 bearing preferably in the form of a stud 14 in the end of the bracket 12 and I journal on this bearing the driven element of the bunch builder mechanism which is illustrated as a segmental gear 15. This gear 15 may be made in one part, but is preferably 35 made in half sections 16 and 16^a, having a common hub portion adapted to be mounted on the bearing 14 and having aligning teeth on their lapped peripheral edges. The sections 40 are adapted to be interlocked by a bolt 17, and extra bolt hole or holes 18 are provided in the section 16^a if it be desired to reduce the arc subtended by the assembled segmental gear beyond that shown in Fig. 3. 45 Each gear section is provided with a group of end teeth 19 which are drawn in on a decreasing radius for the purpose of easing the builder rack upwardly, as the segmental gear runs out of mesh at either end with the 50 driving gear 11, and avoiding a sudden jump when the builder rack is restored to the control of the builder cam 9 at the completion of the winding of the bunch. In order that the requisite traverse may be provided for 55 the proper winding of the bunch the gear 15 is provided between the teeth 19, with spaced groups of high teeth 20 and 21 and interposed groups of low teeth 22, the periphery of the gear being indented so as to set 60 the teeth 22 with the proper pitch much closer to the axis of the gear than the teeth 20, 21, and by this arrangement the builder rack, which is held downward against the weight of the ring rail by the engagement of 65 the gears 15 and 11, will have a rise and fall

imparted to it sufficient to give a traverse for winding the bunch. When it is desired to shorten the length of the bunch the bolt 17 will be engaged in the hole 18 which will bring the sets of teeth 21 and 20 of gear section 16 into alignment respectively with the sets of teeth 20 and 21 of gear section 16^a. The gear 11 is wide enough to mesh the teeth of both segmental gear sections and thus I provide for the lengthening and shortening of 70 the period of engagement between the driving and driven gears, which period determines the time the yarn is being wound to form the bunch. I have shown only two 75 adjustments, but obviously the number may be increased by the same means. 80

The segmental gear will normally hang by gravity with its teeth below position to mesh the gear 11, which is the position shown in Fig. 1, and I will now describe the mechanism for automatically bringing the bunch building mechanism into operation. 85

I screw a stud bolt 23 into the drum 2 and place a spacer 24 around the bolt as a simple means of providing an offset bearing for a 90 latch 25 that is thus mounted in position to clear the outer face of the gear 11 and to swing in a vertical plane adjacent to the outer face of the segmental gear. Near the free end of this latch in its under edge I provide an inclined notch 26 which in certain 95 positions of the latch is adapted to engage a pin 27 fast on the outer gear section 16 which also carries immediately below the pin 11 a larger boss or lug 28 which is of such shape and size that it will not engage in or enter the notch 26 when it engages and supports the latch as shown in Fig. 5.

In operation, the latch bearing 23 is mounted in the drum 2 in such position that when the drum stands with the chain 3 unwound, which is the position it assumes when the frame has been filled and is ready for doffing, the latch will rest on the pin 27 with its notch 26 beyond the pin. When the ring rail has 105 been lowered and slack has been placed in the traverse chain 4, the builder rack by reason of its weight will swing down about its pivotal support 29. As a part of the doffing operation, the drum 2 is wound up to 110 take up this slack in the traverse chain, and as shown it will be wound in the direction of the arrow in Fig. 1. As it is rotated the latch 25 will be drawn to the left until its notch 26 drops over and engages the pin 27. The 115 continued rotation of the drum will carry with it the latch and swing the segmental gear on its axis 14 until the teeth 19 mesh the gear 11, see Fig. 4, and in this position the segmental gear will be held until the frame 120 is started up. When the frame is started up, the gear 11 will commence to rotate counterclockwise and will rotate with it the segmental gear, causing its boss 28 to move between the pin 27 and the latch bearing 23 and 125 130

thus automatically to lift and disengage the latch from the pin 27, after which the latch will ride on the boss until the segmental gear has run out of mesh with gear 11 when the end of the latch beyond the notch 26 will drop onto the pin 27 and will ride thereon. As the drum 2 is unwound during the filling of the frame it shifts the latch to the right, causing its inclined notch to ride over and stand beyond the pin 27, as shown in Fig. 1, when the latch is ready for the operation to be repeated.

The segmental gear is set so that when its high teeth 20 or 21 are in mesh with the gear 11, a high point on the builder cam 9 will be touching the main pitman roller 8. From this it follows that the low teeth 22 on the segmental gear can follow up and mesh the gear 11 since the pitman roller 8 will then be opposite a low point of the builder cam. It is equally obvious that while the gears 16 and 11 are engaged the builder rack cannot follow to the low points of the main builder cam 9 but only as far as the low teeth 22 on the segmental gear will permit. Hence, the main builder cam and its pitman roller will not co-act so as to interfere with the operation of building the bunch, nor will the bunch building mechanism hold the pitman roller so as to block the main cam as the builder rack is at all times free to move downwardly if a high point of the cam 9 happens to touch the pitman roller while low teeth on the gear 16 are meshing the gear 11. Moreover, since the segmental gear takes control of the builder rack when the latter is in the position where it would be set by the engagement of a high point on the builder cam with the main pitman roller, it follows that the bunch 32 will be built in the proper place at the base of the feeler wood 33. As soon as the bunch building gears have run out of mesh, the teeth 19 will ease the rack 1 back into position for its roller 8 to be picked up and thereafter controlled by the main builder cam, and during the application of the main service windings the segmental gear 16 will hang idle out of position where it could interfere in the least. It is important to note the extreme simplicity of this mechanism for automatically accomplishing the objects needed, it requiring only the mounting of the gear 11 on the cam shaft, the mounting of the bracket 12 on the builder rack bolt 13, and the pivoting of the latch to the drum 2, and with these simple changes the device can be applied to any type of spinning frame in which the ring rail is lowered to doff.

Though I have described with great particularity the details of the embodiment of the invention herein shown, it is not to be construed that I am limited thereto, as changes in arrangement and substitution of equivalents may be made by those skilled in

the art without departing from the invention as defined in the appended claims.

By the expression in the claims that the bunch builder mechanism in operation intercepts control of the builder rack by the main builder cam, I mean that such interception prevents the laying of windings other than in the bunch, it being obvious that a tip of the builder cam might engage and lower the builder rack to lay windings at the top of the bunch or so close thereto as not to interfere materially with the winding of the bunch. My purpose is attained so long as the engaging, driving and driven elements of the bunch builder mechanism will prevent the builder rack moving substantially out of a range of positions required for the building of a satisfactory commercial bunch.

Having thus described my invention, what I claim as new and desire to secure by Letters Patent, is:—

1. In a bunch builder attachment for spinning frames, a driving element rotatable with the builder cam, a driven element in engagement with the builder rack and adapted to stand normally disengaged from said driving element, and means, responsive to the winding of the traverse chain, to bring the driving and driven elements into engagement, said elements while engaged being adapted to intercept control of the builder rack by the builder cam.

2. In a bunch builder attachment for spinning frames, a driving element rotatable with the builder cam, a driven element in engagement with the builder rack and adapted to stand normally disengaged from said driving element, and means, responsive to the winding of the traverse chain, to bring the driving and driven elements into engagement, said elements while engaged being adapted to intercept control of the builder rack by the builder cam and give a traverse for the winding of the bunch.

3. In a bunch builder attachment for spinning frames, a driving element rotatable with the builder cam, a driven element mounted to rotate on the builder rack and adapted to stand normally disengaged from said driving element, and means, responsive to the winding of the traverse chain, to bring the driving and driven elements into engagement, said elements while engaged being adapted to intercept control of the builder rack by the builder cam to give a traverse for the winding of the bunch.

4. A bunch builder attachment according to claim 1, in which the driven element is adapted to hang out of position to engage the driving element during the application of the main service windings to the bobbins.

5. In a bunch builder mechanism for spinning frames, a driving element rotatable with the builder cam, a driven element in engagement with the builder rack and adapted to

- stand normally disengaged from said driving element, means automatically responsive to an operation incidental to doffing the frame for moving said elements into engagement, side elements while engaged being adapted to intercept control of the builder rack by the builder cam, and means movable with one of said elements to disengage and reset said means for moving said elements into engagement.
6. A bunch builder mechanism according to claim 5, in which the disengaging and resetting means are carried by the driven element.
15. 7. A bunch builder attachment for spinning frames, comprising a driving gear rotatable with the builder cam shaft, a segmental gear mounted to rotate on the builder rack and disposed normally out of position to engage said driving gear, a latch movable responsive to the winding of the traverse chain and adapted as it moves to engage and rock the segmental gear into mesh with said other gear, and trip means on the segmental gear to release the latch after said gears are in mesh, said gears when in mesh being adapted to intercept control of the builder rack by the builder cam for the purposes described.
30. 8. A bunch builder attachment according to claim 7, in which the latch is pivotally mounted on the winding drum for the traverse chain.
9. A bunch builder attachment according to claim 7, in which the latch is pivotally mounted on the winding drum for the traverse chain and the segmental gear has a pin which said latch engages.
10. A bunch builder attachment according to claim 7, in which the latch is pivotally mounted on the winding drum for its traverse chain and the segmental gear has a pin which said latch engages, said trip means being a stud too large to enter said notch.
45. 11. In a bunch builder attachment for spinning frames, a gear rotatable with the builder cam shaft, a segmental gear mounted to rotate on the builder rack and normally standing out of position to engage said other gear during the application of the main service windings to the bobbin, a latch pivotally attached to the drum for the traverse chain, a pin on the segmental gear to be engaged by the latch, and as the drum is wound to move the segmental gear into mesh with the other gear, and a stud on the segmental gear disposed to release the latch from the pin as the segmental gear is driven, said gears when in mesh being adopted to intercept control of the builder rack by the builder cam.
12. A bunch builder mechanism according to claim 7, in which the segmental gear has a pin and a larger trip stud, and the latch has an intermediate notch too small to drop over said stud and spaced far enough from the free
- end of the latch to permit the latter to ride always on said stud or pin, as and for the purposes described.
13. In a bunch builder attachment for spinning frames, a driving element rotatable responsive to the main builder cam shaft, an element mounted on the builder rack, means to bring said elements into engagement automatically responsive to a doffing operation, said elements while in engagement being adapted to intercept control of the builder rack by the builder cam, and means to adjust the effective length of the element mounted on the builder rack to vary the period of engagement between said elements, as and for the purposes described.
14. A bunch builder attachment according to claim 13, in which said elements are gears, the element on the builder rack being a segmental gear formed of lapped sections which can be adjusted to vary the arc subtended by the toothed periphery of such gear.
15. A bunch builder attachment according to claim 13, in which the elements are gears, the element on the builder rack being a segmental gear formed of lapped sections which can be adjusted to vary the arc subtended by the toothed periphery of such gear, there being high and low teeth on said segmental gear to effect a traverse for the building of the bunch.
16. In a bunch builder attachment for spinning frames, a driving element rotatable responsive to the main builder cam shaft, an element mounted on the builder rack, means to bring said elements into engagement automatically responsive to a doffing operation, said elements while in engagement being adapted to intercept control of the builder rack by the builder cam, and means to adjust the effective length of one of said elements to vary the period of engagement between said elements, as and for the purposes described.
- In testimony whereof I affix my signature.
- HOMER H. HOLCOMBE.
